UNITED STATES PATENT OFFICE.

ARA B. EDWARDS AND CHARLES A. TURNER, OF HAMLET, NORTH CAROLINA, AND
THOMAS L. REED, OF ATLANTA, GEORGIA.

VALVE-CHANGING MEANS.

1,353,114.

Specification of Letters Patent. Patented Sept. 14, 1920.

Application filed October 16, 1918. Serial No. 258,364.

To all whom it may concern:

Be it known that we, ARA B. EDWARDS, CHARLES A. TURNER, and THOMAS L. REED, citizens of the United States, residing at 5 Hamlet, county of Richmond, State of North Carolina, Hamlet, county of Richmond, State of North Carolina, and Atlanta, county of Fulton, State of Georgia, respectively, have invented new and useful 10 Improvements in Valve-Changing Means, of which the following is a specification.

Our present invention pertains to valve changing means for locomotives and the like.

15 The object of the invention is the provision of an organized mechanism whereby fluid under pressure, preferably compressed air, is utilized to advantage in the changing of the valve gear, thereby rendering unnecessary the expenditure of more than 20 slight initial effort on the part of the locomotive engineer.

To the attainment of the foregoing, the invention consists in the combination with 25 manual means for initially adjusting the valve gear, of means actuatable by fluid under pressure for completing the necessary movement and really effecting such movement.

30 The invention also consists in the interpolation of the fluid pressure mechanism in the connection intermediate the manually operable means and the valve gear, whereby said fluid pressure mechanism is 35 promptly controlled by said manual means.

The invention further consists in certain details calculated to contribute materially to the efficiency of the improvement as a whole.

40 With the foregoing in mind, the invention will be fully understood from the following description and claims when the same are read in connection with the drawings accompanying and forming part of 45 this specification, in which:

Figure 1 is a view showing in side elevation the construction constituting the best practical embodiment of our invention that we have as yet devised.

50 Fig. 2 is an enlarged view, partly in longitudinal vertical section and partly in elevation, illustrative of the arrangement of the fluid pressure mechanism relative to the reach rod employed as an adjunct to 55 the reverse lever. In this view the piston

of said mechanism is shown in neutral position.

Fig. 3 is an enlarged detail view showing the control valve of the fluid pressure mechanism in position to change the locomotive balanced valve to bring about forward movement of the locomotive.

Fig. 4 is an enlarged detail view showing one of the valves for controlling the exhaust from the piston cylinder of the fluid pressure mechanism.

Fig. 5 is a transverse section, taken in the plane indicated by the line 5—5 of Fig. 4.

Similar numerals of reference designate 70 corresponding parts in all of the views of the drawings.

The balanced valve 1 shown in Fig. 1 may be and preferably is of the ordinary well known construction, and this is also 75 preferably true of the valve gear including among other elements the tumbler shaft 2, the lever 3 thereon, the arm 4 also carried by said shaft, the rocker 5 and the valve stem rod 6.

At 7 and designed to be located in the locomotive cab is an ordinary reverse lever, operable in the usual manner and equipped with a suitable detent 8 whereby it may be 80 adjustably fixed to a segmental rack 9.

The lever 7 is connected with the lever 3 by the means which constitute the subject matter of our invention.

In furtherance of our invention we extend the sectional reach rod 10 through a cylinder 11, and we suitably fix upon said rod a piston 12. We also equip the cylinder 11 with a valve chest 13 which is designed to be connected through a pipe 14 with a suitable source of fluid pressure supply. 90 We further dispose a slide control valve 15 in the chest 13, and provide the rod 10 with a lateral arm 16, suitably fixed upon the rod and movable on a guide rod 17, and connected through a link 18, a lever 19, and a 95 stem 20 with the member 21 of the said slide control valve. The valve member 21 is capable of limited movement with respect to the major valve member 22; and it will be noted that the member 21 is provided with bleed openings 23, while the member 22 is provided with ports 24, designed to communicate with the said bleed openings 23 and to be uncovered alternately by the valve member 21, and to register with the ports 100

105 member 21, and to register with the ports 110

25 leading to the opposite ends of the interior of the cylinder.

Also in furtherance of our invention we provide complementary to the cylinder 11 5 the exhaust means clearly shown in Figs. 2, 3, 4, and 5. The said means includes a conduit 26, formed in the rod 10 and communicating with the cylinder interior at the forward side of the piston 12, a conduit 10 27 also formed in the rod 10 and communicating with the cylinder interior at the rear side of the piston 12, a spring pressed exhaust valve 28 for controlling the conduit 26, a spring pressed exhaust valve 29 for 15 controlling the conduit 27, and an abutment 30 for opening the exhaust valve 28 upon forward movement of the reach rod 10, and for opening the exhaust valve 29 upon rearward movement of said reach rod. 20 The manner in which the abutment 30 operates to open the valve 28 and 29 alternately will be readily understood when it is stated that the said valves and the conduits that they control are carried by one section 40 25 of the reach rod 10, while the abutment or tappet 30 is carried by the rear rod section 41; the said section 41 being longitudinally slotted at 42 to receive a lateral pin 43 on the section 40, whereby the two 30 sections are connected in such manner that the section 41 is capable of limited movement independently of the section 40.

In the practical operation of our improvement when the valve 1 is in neutral 35 position and the piston 12 is also in neutral position as shown in Fig. 2, the engineer in order to change the valve 1 so as to bring about forward movement of the locomotive has but to move the lever 7 forwardly in the conventional manner. Upon 40 the said forward movement of the lever 7 the tappet 30 first opens the exhaust valve 28 to permit fluid under pressure to escape from the interior of the cylinder 11 at 45 the forward side of the piston 12. The said forward movement of the rod 10 being continued the control valve 15 is moved to the position shown in Fig. 3, whereupon a considerable head of fluid under pressure 50 will be admitted to the cylinder 11 at the rear side of the piston 12 and will result in the changing of the valve 1 being effected by fluid under pressure.

When the piston 12 is in neutral position 55 and it is desired to move the locomotive backwardly, the operation described is reversed—*i. e.*, the tappet 30 first opens the exhaust valve 29, and then the manual rearward movement of the reach rod 10 being 60 continued, the control valve 15 will be moved toward the left in Fig. 2 so as to admit a considerable head of fluid under pressure to the cylinder 11 in front of the piston 12 whereupon the valve 1 and the 65 valve gear will be moved by the fluid under

pressure. From this it is thought the operation incidental to changing from forward movement of the locomotive to backward movement thereof and vice versa will be readily apparent and need not therefore be set forth in detail.

When the control valve 15 is adjusted as described the bleed openings 23 in the member 21 of said valve serve to admit a small volume of fluid under pressure to the portion of the cylinder 11 that is for the time being open to the atmosphere, this with a view to cushioning the movement of the piston 12 under the action of the greater volume of fluid under pressure admitted through one of the uncovered ports 24. This will be fully appreciated by reference to Fig. 3.

It will be manifest from the foregoing that incidental to the operation of our improvement the changing of the valve 1 is practically accomplished by the fluid under pressure, it being obvious that but very little effort on the part of the engineer is necessary to first move the rod 10 as a whole sufficiently far to bring about the required movement of the control valve 15. It will also be manifest that because of its arrangement relative to the reach rod 10, our improvement is compact and therefore, takes up but little space as part of the equipment of a modern locomotive.

Having described our invention what we claim and desire to secure by Letters-Patent is:

1. The combination in locomotive control equipment, of manually operable means, a reach rod comprising a member connected with said means and having a tappet and a second member with respect to which the first named member has a limited movement, the said second member carrying a piston and having exhaust conduits extending to opposite sides of the piston, valves carried by the second member and controlling said conduits and disposed at opposite sides of and adapted to be opened alternately by the tappet of the first member, a cylinder surrounding the second member of the reach rod and inclosing the piston, a valve chest carried by said cylinder and adapted to be connected with a source of fluid pressure supply, ports intermediate the valve chest and the interior of the cylinder at opposite sides of the piston, a control valve movable in said chest and having ports and also having a minor member in which are bleed ports for use in conjunction with the said ports, said minor member being capable of limited movement with respect to the remainder of the control valve, and a connection between the forward member of the reach rod and the minor member of the control valve for moving the latter by the former.

2. In locomotive control equipment, the combination of manually operable means, a reach rod comprising a forward section carrying a piston and having exhaust conduits extending from opposite sides of the piston, normally closed valves on said section and controlling said conduits, a rear section connected with the manually operable means and also connected with the forward section and constructed and arranged to have a limited movement with respect to the same and provided with a tappet for alternately opening the exhaust valves, a cylinder surrounding the forward section of the reach rod and inclosing said piston, said cylinder having ports leading to opposite sides of the piston, valve means for controlling the supply of fluid under pressure to said ports, and a connection intermediate the forward section of the reach rod and said valve means for moving the latter by the former.
3. In locomotive control equipment, the combination of a balanced valve, valve gear connected therewith, manually operable means, fluid pressure mechanism comprising a cylinder and piston having inlet and exhaust ports, and a sectional reach rod intermediate the manually operable means and the valve gear and comprising a section connected with the piston forming part of the fluid pressure mechanism and a section movable independently of the first named section and adapted to control the exhaust of the fluid pressure mechanism, and valve means actuatable by the first named section of the reach rod for controlling the supply of fluid under pressure to effect the movements of the reach rod.
4. In means for the purpose described, the combination of a sectional reach rod, one section having conduits and spring pressed valves for controlling said conduits, a piston on said rod between the inner ends of said conduits, a cylinder inclosing said piston, and means for supplying fluid under pressure to said cylinder, and a section capable of limited movement with respect to the first named section and having a tappet for alternately moving the valves thereof against the action of their springs.
5. In means for the purpose described, the combination of a cylinder divided by a piston into chambers and having ports extending to said chambers, a valve chest inclosing said ports and adapted to be connected with a source of fluid pressure supply, a slide valve comprising a member having ports adapted to register with those of the cylinder, and a second member movable independently of the first named member and adapted to uncover the ports thereof and having bleed ports for registration with the ports of the first named member, and means connected with the second named member of the valve for actuating the valve.

In testimony whereof we affix our signatures.

ARA B. EDWARDS.
CHARLES A. TURNER.
THOMAS L. REED.
